UNITED STATES PATENT OFFICE.

VICTOR JOSEPH TOUCHARD, OF PARIS, FRANCE.

WATER-HEATING DEVICE.

1,072,274.

Specification of Letters Patent.

Patented Sept. 2, 1913.

Application filed August 29, 1912. Serial No. 717,781.

To all whom it may concern:

Be it known that I, VICTOR JOSEPH TOUCHARD, a citizen of the French Republic, and resident at Rue Beaugrenelle 14, Paris, France, have invented certain new and useful Improvements in Water-Heating Devices, of which the following is a specification.

My present invention relates to water heating devices capable of quickly heating water particularly for use in households or medicinal purposes. Devices of this kind heretofore known are objectionable in that they require special arrangements and be- 10 sides are not permanently ready for use. These objections are completely removed by my present invention, which has for its object to provide a device for quickly heating water for use in households or medicinal 15 purposes, in which water is heated within a manifold coil-tube by means of a burner.

One feature of the invention consists in using a coil tube, which is coiled in horizontal and vertical directions and arranged 20 within a comparatively small removable casing, adapted to be directly fitted upon any existing burner.

The purpose of the invention is to produce 25 hot water immediately after the burner is ignited, which is very important for medicinal or domestic purposes.

My invention will be readily understood 30 from the following description taken in connection with the accompanying drawings, 35 wherein I have illustrated several constructions of my invention.

In these drawings:—Figure 1.—shows a longitudinal section, Fig. 2.—is a cross-section on line A—B of Fig. 1; Fig. 3.—shows 40 another form of construction, and Figs. 4 to 7.—show different coil-tubes.

Secured to the gas-cock 2 is a Bunsen burner 1, provided with a controlling device 3, whereby the admission of air may be controlled. Arranged at the upper end of the burner provided with a sieve, is a sievelike hood 4, whereby the flame is distributed upon the whole area of cross-section of the casing. The sieve 4^a serves merely to prevent the flame from flashing back into the burner. The tube of the burner is moreover provided with an annular shoulder 5, serving to support the bottom 6 of the casing 8, whereby the latter is held in position. 50 The bottom 6 of the casing 8 is provided at

its outer periphery with a flange 7, through which extend the fastening bolts 12 of the cover 10, having also a peripheral flange 11. The fastening bolts 12 extend preferably through tubes 13, which however may be replaced by flanges or shoulders provided on said bolts. Screw-nuts 14 are provided to secure the bolts 12 in position. The casing is provided with openings 9 for the admission of sufficient quantities of combustion air. Arranged within the casing is coiled water-heating tube 15, which forms a horizontal coil as shown in Fig. 1. Water is admitted into the same at 16 and discharged from the same at 17, and to this end the inlet of the coil is provided with a screw-threaded extension 18, while the outlet is provided with a similar extension 19. To these extensions 18 and 19 are connected admission and discharge-pipes 20 and 21 re- 60 spectively by means of suitable coupling nuts. As some water may be accumulated within the casing owing to the condensations produced within the latter, I have provided said casing with a discharge-pipe 22, where- 65 by condensed water may be discharged from the casing.

The gas-pipe is provided with a valve 23 of usual form, journaled in the bulged portion 24. Said gas-pipe is moreover provided with a small tube 25, which leads the gas in close proximity to the upper end of the burner, the gas discharged from said tube being permanently ignited, so that it will be sufficient to open the valve 23 for bring- 70 ing the device into operation.

The igniting device is composed of a cock 26, a second cock 27 and a coupling nut 28, which secures the tube 25 to the cock 27. The mouth of the tube is provided with 75 small openings 29 for the igniting flame and for the purpose of securing good burning of the same.

The modified form shown in Fig. 3 is distinguished merely by the arrangement of a modified Bunsen burner, provided with a mouth-piece 30 for a flexible tube, whereby the device may be placed at any desired place. 80

In Figs. 4 and 5 I have illustrated a coiled water-heating tube 15^a, the admission and discharge openings 18^a and 19^a of which are arranged in front of each other; said tube has a plurality of horizontally arranged series of coils, so that water is brought from the bottom to the top and then discharged 85 100 105 110

from the heating device through the opening 19^a.

Figs. 6 and 7 show another modification of the coiled water-heating tube, which in contradistinction to the forms described, has the advantage that water flows upwardly through the portion *a* of the coiled tube 15^b and downwardly through the portion *b* of said tube, whereupon the water is brought 10 into the portion *c* of the coiled tube, through which it flows again upwardly and then again downwardly through the portion *d*, the hot water being finally discharged through the opening 19^b. The extension 18^b 15 serves to admit water into the coiled tube.

The device operates as follows:—If it is desired to heat water, the valve 23 is opened and the gas is ignited. At the same time the cock of the water supply-pipe is opened, so 20 that water is admitted into the coiled tube. Owing to the arrangement of the casing and the comparatively small cross-section of the coiled tube made of copper or other suitable metal, and owing to the great number of 25 windings, the water will be heated instantly, so that shortly after the ignition of the gas hot water may be taken from the device.

As already described, the device is preferably provided with a continuously burning igniting flame so that the gas discharged from the burner needs not be ignited manually at each operation. After the use, the valve 23 is turned off, whereby the device is brought out of operation.

Of course the water heating device herein 35 described may also be placed upon any other gas-burner.

I claim:

In an apparatus for the heating of water, the combination with a casing comprising a 40 drum formed with air inlet and outlet openings, of a bottom on the drum, said bottom having an annular vertical wall and a horizontal flange extending from said vertical wall, the lower portion of the drum being 45 supported on the bottom and fitting snugly against the vertical wall, a top for the drum, the top extending between the vertical plane of the drum, sleeves interposed beyond the 50 extended portion of the top and the horizontal flange of the bottom, bolts extending through the top, the horizontal flange and the sleeves to lock the casing together, a series of vertically disposed coils in the drum, the coils being spaced apart to form a central vertical passage, water inlet and outlet pipes connected with the coils, a burner in the bottom of the casing in alignment with the central vertical passage between the 55 coils, and means for controlling the burner. 60

In testimony whereof I have hereunto set my hand in presence of two witnesses.

VICTOR JOSEPH TOUCHARD.
